United States Patent Office

Des. 218,083
Patented July 14, 1970

218,083

BEVERAGE DISPENSER

Robert B. Hartley, Columbia Heights, Minn., assignor to
The Cornelius Company, Anoka, Minn., a corporation of Minnesota

Filed Jan. 30, 1969, Ser. No. 15,569

Term of patent 14 years

Int. Cl. D15—12

U.S. Cl. D94—3

Fig. 3

Fig. 4

FIG. 1 is a perspective view of a beverage dispenser, embodying my new design, showing the front and one side thereof.

FIG. 2 is a perspective view thereof showing the opposite side and rear thereof.

FIG. 3 is an enlarged front elevational view thereof.

FIG. 4 is a top plan view thereof.

FIG. 5 is a side elevational view thereof, the opposite side having a reverse appearance.

FIG. 6 is a front perspective view of another embodiment thereof which is otherwise similar to the embodiment of FIG. 1.

I claim:

The ornamental design for a beverage dispenser, substantially as shown and described.
